[57] CLAIM

The ornamental design for a garden weeder, as shown and described.

DESCRIPTION

FIG. 1 is a front elevational view of a garden weeder showing our new design, the rear being identical thereto; FIG. 2 is a right side elevational view thereof, the left side being a mirror image thereof;

FIG. 3 is a large scale fragmentary front elevational view thereof showing the head portion thereof and a portion of the handle shaft thereof;

FIG. 4 is a large scale bottom plan view thereof; and,

FIG. 5 is a larger scale top plan view thereof.
